UNITED STATES PATENT OFFICE.

JAMES W. RAMSDELL, OF HIGHLAND PARK, MICHIGAN.

SANITARY DRINKING-FOUNTAIN.

1,278,998.

Specification of Letters Patent. Patented Sept. 17, 1918.

Application filed April 7, 1917. Serial No. 160,413.

To all whom it may concern:

Be it known that I, JAMES W. RAMSDELL, a citizen of the United States, residing at Highland Park, in the county of Wayne and State of Michigan, have invented certain new and useful Improvements in Sanitary Drinking-Fountains, of which the following is a specification.

This invention relates to drinking fountains, and especially to that type of fountain known as bubble cup, although having considerable differences from the bubble cups as ordinarily used. Such cups as commonly used have a central mouth piece with a jet 15 hole therein, to which the lips of the drinker are applied. This is unsanitary, because there is a possibility that bacteria or germs may be left on the mouth piece or upon the parts which come in contact with the faces 20 of the users. The object of the present invention is to provide a drinking fountain which is free from these objections, and this is accomplished by causing the jet to flow in a curve from the cup or bowl, from an 25 orifice so located that the mouth of the user cannot be applied thereto, but the drinker drinks at the crest of the stream several inches from the jet opening, and, furthermore, the water after it passes his lips does 30 not flow over or upon the mouth piece, but goes at once to waste. By the means described a sanitary drinking fountain is provided, free from any possibility of contamination.

The invention is illustrated in the accompanying drawings in which—

Figure 1 is a section of the fountain.

Fig. 2 is a plan view thereof.

Referring specifically to the drawings, 40 indicates a cup or bowl, and this is conveniently oval in plan, as shown in Fig. 2. A waste outlet is indicated at 7, at the bottom of the bowl.

In the side wall of the bowl, preferably 45 at the end of its longer axes, is a jet orifice 8, to which water is supplied through a passage 9 from a supply pipe 10, controlled for example by a push valve 11. The location and direction of the orifice 8 is such that

a stream issuing therefrom will describe a 50 parabola within the cup, with its crest or highest point at about the level of the rim of the cup, and about the center thereof, the stream finally striking the opposite end of the cup and flowing to waste. The location 55 of the jet opening 8 is such that it is practically impossible for the lips of the drinker to be applied thereto, but the jet rising to the position described is in such location that the mouth of the drinker can be readily applied thereto. The waste from the lips of the drinker falls directly into the cup, and out through the waste pipe and does not by any manner of means come in contact with the jet opening or pass over or around the same. 60

If desired, an extending part 12 may be formed on the inner wall of the cup, hanging over and extending beside the jet orifice, so as to positively prevent any person's lips being applied to the jet orifice and to 70 prevent dirt or foreign matter dropping thereon, and to some extent prevent a person placing his hands upon or about the opening.

The device constructed according to the invention will have the edges indicated and 75 will be serviceable to users who would otherwise be deterred by the fear that the lips of other persons have been applied to the mouth piece, as in the common type of bubbling cups. 80

I claim:

1. A drinking fountain comprising a cup having an internal conduit in the side wall thereof, terminating in a jet orifice in position to discharge a stream upwardly over 85 the central part of the cup, and a shield projecting from said wall above said orifice and extending inwardly and downwardly to a vertical plane beyond that of the orifice and overhanging the same to prevent access of a 90 user's mouth thereto and to prevent drip from his mouth falling thereon.

2. A drinking fountain comprising a cup having a waste outlet in the bottom and an integral conduit terminating in a jet orifice 95 in the side wall thereof located above said outlet and below the rim of the cup, said orifice being directed at an inclination up-

wardly over the waste outlet, and a shield projecting from the rim of the cup above said orifice and extending inwardly and downwardly beyond the vertical plane of said orifice, whereby to prevent access of a user's mouth to said orifice and to prevent waste or drip from his mouth falling thereon.

In testimony whereof, I do affix my signature in presence of two witnesses.

JAMES W. RAMSDELL.

Witnesses:

WALTER S. SIMPSON,
J. EMMET HALL.
